CLAIM

We claim the ornamental design for a housing of an exercise device, as shown and described.

DESCRIPTION

FIG. 1 a side, top perspective view of a housing of an exercise device;

FIG. 2 is a close-up perspective view of the housing of the exercise device of FIG. 1;

FIG. 3 is a rear perspective view of the housing of the exercise device of FIG. 1;

FIG. 4 is a first side view of the housing of the exercise device of FIG. 1;

FIG. 5 is close up side view of the housing of the exercise device of FIG. 4; and,

FIG. 6 is a rear view of the housing of the exercise device of FIG. 1.

The ornamental design that is claimed is shown in solid lines in the drawings. The evenly spaced broken lines shown in the figures are for the purpose of showing environment and form no part of the claimed design.

1 Claim, 4 Drawing Sheets
